Arthur B. Jenkins,
ATTORNEY.

UNITED STATES PATENT OFFICE.

EUGENE G. REISING, OF EAST HARTFORD, CONNECTICUT, ASSIGNOR TO THE HARTFORD MACHINE GUN COMPANY, OF HARTFORD, CONNECTICUT, A CORPORATION OF CONNECTICUT.

FIRING-PIN FOR FIREARMS.

1,313,912.

Specification of Letters Patent. Patented Aug. 26, 1919.

Application filed January 2, 1917. Serial No. 140,174.

To all whom it may concern:

Be it known that I, EUGENE G. REISING, a citizen of the United States, residing at East Hartford, in the county of Hartford and State of Connecticut, have invented a new and Improved Firing-Pin for Firearms, of which the following is a specification.

My invention relates to the class of devices that are employed in firearms to strike the cartridge and cause its explosion; and an object of my invention, among others, is to provide a device of this class that shall be simple and durable in its construction and particularly one in which the firing tip may be readily removed from or replaced on the main part of the pin.

One form of device embodying my invention and in the construction and use of which the objects herein set out, as well as others, may be attained, is illustrated in the accompanying drawings, in which—

Figure 1 is a detail view in central longitudinal section through a breech-bolt containing my improved firing pin.

Fig. 2 is a side view of my improved firing pin with parts thereof cut in central longitudinal section.

Fig. 3 is a detail side view of a portion of the body of the pin.

In the accompanying drawings the numeral 5 indicates a breech-bolt that may be of any ordinary material and constructed in any desired manner, that herein shown having a rib 6 extending along the bottom 25 at its rear end and within which a sear or sears 7 are pivotally mounted and that may be operated by means of a trigger or other members (not herein shown) in a manner that will be readily understood by those skilled in the art, and the invention forming the subject matter of this application having to do with the firing pin only the illustration and description herein is sufficient for a correct understanding of my invention.

The firing pin comprises a body 8 that is in the usual form of a rod having threaded ends 9 and 10. A head 11 is secured to the screw threaded end 10, said head having a neck 12 projecting inwardly and inclosing a portion of the body of the pin as shown in Fig. 2 of the drawings. The sear or sears 7 act against the shoulder 13 at the end of the neck 12 to hold the firing pin 55 in its cocked position in the breech-bolt, to

which cocked position it is moved as by means of a lever (not shown herein) which acts against the shoulder 14 at the inner end of the head 11, it being understood that said lever acts to move the breech-bolt 60 backwardly in its chamber in the receiver and at the same time said lever acts against the shoulder 14 to move the firing pin backwardly in the breech-bolt until it is engaged by the sear 7, in which position the 65 firing pin is held until released by movement of the sears. The sears are held in such engagement by means of a spring pressed plunger 15 as shown in Fig. 1 of the drawings. A collar 16 is secured to the 70 body 8 in any suitable manner and in connection with a retaining pin 17 extending through an opening 18 in the breech-bolt serves to limit the backward movement of the firing pin within said bolt. A spring 75 19 is employed to hold the firing pin at the forward limit of its play in a manner common to devices of this class. A flange 20 is formed on the body of the firing pin, this flange having means to receive and retain 80 a lock. In the form of construction herein shown this means preferably consists of slots 21 formed on diametrically opposite sides of the flange 20. A firing tip 22 fits the screw threaded end 9 of the body of the pin and is 85 screwed up against the flange 20, as shown in Figs. 1 and 2 of the drawings.

A lock 23 is mounted to slide on the body 8, this lock being in the form of a collar and having locking prongs 24 extending through 90 the slots 21 and into notches 25 in the back edge of the firing tip 22, and as shown in Fig. 1 of the drawings. The firing tip is held in its locked position as by means of the prongs 24 extending from the lock 23 95 through the slots in the flange 20 on the body 8 and into the recesses 25 in said tip.

The construction herein illustrated and described provides a very simple and durable means for removably securing the firing 100 tip to the body of the pin, the lock 23 being placed upon the pin from its rear end before the other parts are placed in position.

In accordance with the provisions of the patent statutes, I have described the principle of operation of my invention, together with the apparatus which I now consider to represent the best embodiment thereof; but I desire to have it understood that the apparatus shown is only illustrative, and 110

that the invention can be carried out by other means.

I claim—

1. A firing pin comprising a body having a threaded end with a flange on said pin and a slot in said flange, a firing tip fitting said screw threaded end, a lock mounted on the body, and a member to unite the lock and firing tip, said member extending 10 through the slot in said flange.
2. A firing pin comprising a body having a threaded end and a flange adjacent to said thread and with a slot in said flange, a firing tip fitting the threaded end and 15 having a notch in its edge, and a lock

mounted upon the body and having a prong extending through said slot and engaging the notch in the edge of the firing tip.

3. A firing pin comprising a body having a thread at one end with a flange adjacent 20 to said thread, a firing tip engaging said thread, a lock mounted upon said body, an interengaging member extending between said lock and tip and passing through a slot in said flange, and a head removably 25 secured to the opposite end of said pin.

EUGENE G. REISING.
